SHEET-FEEDING METHOD AND MACHINE

Louis L. Matthews, Westerly, R. I., assignor
to Maxson Automatic Machinery Company,
Westerly, R. I., a corporation of Rhode Island

Application April 6, 1940, Serial No. 328,368

45 Claims. (Cl. 271—76)

The present invention relates to methods of and machines for feeding sheet material, such as paper and the like. The invention is particularly related to methods and machines involving high speeds, like those used at paper mills for cutting webs from a roll or rolls into sheets, and feeding the sheets, by means of more or less horizontal conveyor tapes, into a layboy or other magazine. The sheets are fed by high-speed tapes to low-speed tapes by which they become overlapped, and it is in this overlapped condition that they arrive in the lay-boy.

It has heretofore been customary, in some machines of the above-described character, to provide long narrow stationary metal waving fingers, snapped on to rods disposed between the tapes, with the tops of the fingers slightly above the more or less horizontal line of the tapes, for the purpose of imparting a long lengthwise stiffening wave to the sheets. In this way, the paper sheets are caused to travel substantially straight lengthwise, permitting their becoming overlapped as they travel from high-speed to low-speed tapes. Without some sort of wave, or other supporting means, the head end of a heavy, soft or thin sheet will sag down in the middle, causing it to become snubbed against the tail of the previously traveling sheet during the slowing down of the latter by the slow-speed tapes. This is as true of narrow sheets constituted of very soft or limp material as of wide sheets constituted of firmer stock. On certain classes of stock, however, it is impossible, because of injury to the stock, to drag the paper over metal waving fingers of the above-described character.

According to the invention illustrated and described in a copending application, Serial No. 327,860, filed April 4, 1940, the waving is effected by means of soft waving members that move freely with the stock, thereby preventing damage to the stock. Even this expedient, however, is not feasible with paper stocks of particularly delicate nature, and with sheets such as printed sheets, which it is desirable not to wave at all.

An object of the invention is to provide a new and improved method and machine for bringing the head ends of the oncoming high-speed sheets up out of the way of the tails of the previously fed, slowed-down sheets. A further object is to prevent the tails of the previously fed sheets from becoming positioned in front of the heads of the next-following sheets. Other objects will be explained hereinafter and will be particularly pointed out in the appended claims.

The invention will now be described in connec-

tion with the accompanying drawing, in which Fig. 1 illustrates a preferred embodiment of the invention; and Fig. 2 illustrates a difficulty encountered in the prior art.

5. A web 3 is illustrated as led from a roll or rolls 50 of paper or similar material between feed rolls 52 and over a stationary bed knife or cutter 4, mounted upon a cutter unit 69. The term "web," "paper," "sheet," or its equivalent, 10 will be employed to denote either a single layer or a plurality of superposed layers of the paper or other material. A rotary cutter 54, operated by mechanism 55, operates with the cutter 4 to cut the traveling web into sheets 56. The invention is equally applicable to use with previously cut sheets. Owing to the feeding action of the rolls 52, aided by gravity, the sheets 56 travel at a downward incline toward high-speed conveyor tapes or belts 2, that are mounted over rolls 10 and 66. During such travel, the heads 62 of the sheets may engage a stationary inclined guide board 71, disposed between the cutter 4 and the tapes 2, or a line of sloping or inclined disposed tapes (not shown), described in a copending application, Serial No. 326,975, filed March 30, 1940. The belts or tapes 2 are disposed approximately horizontal, substantially parallel to the bed knife 4, at a level below the level at which the web is fed between the rolls 15 20 and 66. 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955
- A roll 7 may be employed just back of and close to the roll 68, between the cutters 4, 54 and the tapes 2. It is shown rotated at high speed, higher than the speed of the roll 68, by the mechanism 58, its lower periphery in the direction of travel of the sheet, as indicated by the arrow, to cause it to engage or take up the

tail 67 of each sheet. The roll 7 pulls the tail of each sheet temporarily with greater speed than the speed with which the tapes 2 and 6 pull the body of the sheet to feed the sheet forward toward the lay-boy (not shown).

By temporarily thus pulling the tail end 67 of each sheet forward, in substantially the direction of feed of the sheet, the roll 7 unhooks the said tail end 67 from in front of the fast-traveling rotary knife 54, thus actuating it out of the path of travel of the rotary cutter 54. If the paper becomes "hooked" on the faster-moving rotary knife 54, the roll 7, running at fast speed, and deliberately forming a loop between the fast-running roll 7 and the slower-running roll 68, will unhook it. Further description of this roll 7 may be found in a copending application, Serial No. 327,107, filed April 1, 1940.

The low-speed tapes 72 are mounted over a roll 20. Idler rolls 82 and 84 are frictionally driven by the respective tapes 6 and 72. The idler roll 82 is integral with a slowing-down roll 19 of larger diameter. The low-speed tapes 72 are overlapped by and separated from the high-speed tapes 6, as shown. The sheets are engaged on opposite sides of the tapes 2 and 6 at the time that they travel over the roll 10. The head 62 of each sheet, as it is delivered from between the high-speed tapes 2 and 6, is then caused to travel, lapped over the tail 67 of the prior-fed sheet, between, and unconfined by, the high-speed tapes 6 and the low-speed tapes 72, over the roll 84 and under the slowing-down roll 19. The head of the sheet becomes thereupon engaged between the slowing-down roll 19 and the tapes 72, whereupon the speed of advance of the sheet becomes slowed down.

When dealing with long sheets, however, it is sometimes difficult to make the head end 62 of the high-speed sheets travel smoothly to the slowing-down roll 19, even with the aid of crimpers, no matter of what type. As the head end 62 of the fast-running sheet 56 gets well out over the rear section of slow-running tapes 72, its weight causes it to fall down, so that it eventually comes in contact with the previously fed slow-running sheet 22. At this time, the rear end 67 of the high-speed sheet 56 is still being driven out into space by the high-speed roll 10 and the tapes 6 above and the tapes 2 around the roll 10. This high-speed drive from the rear, and this slow-speed contact at the front end 62 of the sheet, coupled with the fact that the paper has a crosswise bend, caused by the dropping of the front end 62 of the sheet, results in a fold or bend or curl 23, Fig. 2. This, of course, prevents satisfactory operation.

To overcome this difficulty, according to the illustrated embodiment of the invention, a horizontally disposed steel plate or table 24 is provided crosswise of the machine, at about the level of the center of the roll 10. An air current, injected vertically upward against the bottom of this steel table by pipes or nozzles 25, is caused by the steel table 24 to travel horizontally out and forward above the slow-running sheet 22, and beneath the head end 62 of the oncoming high-speed sheet 56. The air is thus blown under the table and beyond the table, under the head 62 of each sheet 56, while it is still traveling at high speed, and just before its change of speed by the low-speed tapes 72, into the space between the high-speed sheet 56 and a previously fed low-speed sheet 22. As the air current is caused to travel faster than the sheet 56, as indicated by

the arrows in Fig. 1, it controls the head of the sheet 56, as the sheet is pushed forward from the rear of the tapes 2 and 6, so as to hold it out straight. The effect is substantially the same 5 relatively as though the sheet were being pulled from the head end. Curling of the head of the sheet is thus prevented, and the fold shown at 23 in Fig. 2 can not occur.

The action may be aided by a small, relatively 10 weak air current, directed vertically upward at 18, through a pipe or nozzle 80, in advance of the roll 10, in the line of feed, and to one side, in back of the roll 20, as described in a copending application, Serial No. 328,367, filed April 6, 15 1940. This blows upward under the heads 62 of the sheets, to buoy them upward, out of the way of the tails 67 of the next-preceding sheets 21, as they leave the high-speed tapes 2, and prior to their being acted upon by the draft from the 20 nozzles 25. The air current 18 acts upon the heads 62 of the sheets 56 as they pass successively the point where the air draft 18 operates, just prior to the time when they enter between the tapes 6 and 72, prior to the time that the air 25 from the nozzles 25 acts thereon, and prior to the time that the speed of the sheets becomes lowered. In the case of very long sheets, the bend 23, Fig. 2, would occur even with the aid of the nozzles 80; without such aid, the sheets 56 might 30 curl in a place even in advance of the point at which the bend or fold 23 is shown. The air at 18 from the nozzles 80 prevents such curling until after the head 62 of the sheet has traveled beyond the influence of the air current 18. By this time, 35 however, it has traveled over and beyond the tail 67 of the next previously fed sheet 22, that has been slowed down by the slow-speed tapes 72. The air draft 18 should be just strong enough to stiffen the head 62 of the sheet and hold it stiffened for a period of time before its speed is 40 changed sufficient to enable it to pass smoothly over the tail 67 of the previously fed sheet 22 and into the influence of the air draft from the nozzles 25. It is found, in practice, that the air from the nozzles 80 is not always needed when the nozzles 25 are employed, but in many cases it is 45 desirable to employ both the nozzles 25 and the nozzles 80. There is, however, a difference in the operation between the air draft from the nozzles 25 and the air draft 18 from the nozzles 80 in that the former continues to blow under the sheet for a substantial distance beyond the point at which the nozzles 25 are located; as indicated by the arrow, this distance may extend 50 to the slowing-down roll 19. The air draft from the nozzles 25 continues to act, in the direction of extension between the low-speed sheet 22 and the high-speed sheet 56, until the speed of the high-speed sheet 56 is actually changed by 55 contact with the tapes 72. The air jet 18 is substantially at right angles to the direction of travel of the high-speed sheet 56, while the air currents from the nozzles 25 are substantially in the same direction as the direction of travel of the sheet.

The air drafts through the nozzles 25 and 80 60 may be produced in any desired way, as by means of a blower, conventionally shown at 73, driven by a motor or in any other desired way, and 65 provided with an adjustable shutter or damper 74 over the central intake hole for regulating the quantity of air in the drafts 18 and 25. If available, the drafts may be supplied from the compressed air line of a mill, or from any other 70 source of air supply.

Modifications will occur to persons skilled in the art, and all such are considered to fall within the spirit and scope of the invention, as defined in the appended claims.

What is claimed is:

1. A method of feeding sheets that comprises feeding sheets at relatively high speed, thereafter feeding the sheets at relatively low speed to cause the sheets to become overlapped in a moving pile, and blowing up under the heads of the sheets while they are still traveling at high speed and until their speed is changed.

2. A method of feeding sheets that comprises feeding sheets at relatively high speed, thereafter feeding the sheets at relatively low speed to cause the sheets to become overlapped in a moving pile, stiffening the head of each sheet, and thereafter blowing under the heads of the sheets while they are still traveling at high speed and until their speed is changed.

3. A method of feeding sheets that comprises feeding sheets at relatively high speed past a predetermined point, thereafter feeding the sheets at relatively low speed to cause the sheets to become overlapped in a moving pile, stiffening the head of each sheet as it passes the point, and thereafter blowing under the heads of the sheets while they are still traveling at high speed and until their speed is changed.

4. A method of feeding sheets that comprises feeding sheets at relatively high speed, thereafter feeding the sheets at relatively low speed to cause the sheets to become overlapped in a moving pile, and pulling upon the heads of the sheets while they are still traveling at high speed and before their change in speed.

5. A method of feeding sheets that comprises feeding sheets at relatively high speed, thereafter feeding the sheets at relatively low speed to cause the sheets to become overlapped in a moving pile, blowing under the head of each sheet to stiffen it, and thereafter pulling upon the heads of the sheets while they are still traveling at high speed and before their change in speed.

6. A method of feeding sheets that comprises feeding sheets at relatively high speed, thereafter feeding the sheets at relatively low speed to cause the sheets to become overlapped in a moving pile, and directing air currents into the space between a high-speed sheet and a previously fed low-speed sheet in the direction of extension between the sheets.

7. A method of feeding sheets that comprises feeding a plurality of sheets at relatively high speed successively past a predetermined point, thereafter feeding the sheets at relatively low speed to cause the sheets to become overlapped in a moving pile, blowing under the head of each sheet to stiffen it as it passes the point, and thereafter continuing to blow under the heads of the sheets while they are still traveling at high speed and until their speed is changed.

8. A method of feeding sheets that comprises feeding a plurality of sheets at relatively high speed successively past a predetermined point, thereafter feeding the sheets at relatively low speed to cause the sheets to become overlapped in a moving pile, blowing under the head of each sheet to stiffen it as it passes the point, and thereafter directing air currents into the space between a high-speed sheet and a previously fed low-speed sheet.

9. A method of feeding sheets that comprises feeding sheets at relatively high speed, thereafter feeding the sheets at relatively low speed to cause

the sheets to become overlapped in a moving pile, and directing air currents under the heads of the sheets, while still traveling at high speed, in substantially the direction of travel of the sheets, at a speed higher than the speed of travel of the high-speed sheets.

10. A method of feeding sheets that comprises feeding sheets at relatively high speed, thereafter feeding the sheets at relatively low speed to cause the sheets to become overlapped in a moving pile, blowing under the head of each sheet to stiffen it, and thereafter directing air currents under the heads of the sheets, while still traveling at high speeds, in substantially the direction of travel of the sheets, at a speed higher than the speed of travel of the high-speed sheets.

11. A sheet-feeding machine having, in combination, means for feeding sheets at relatively high speed, means for thereafter feeding the sheets at relatively low speed to cause the sheets to become overlapped in a moving pile, and means for directing air currents under the heads of the sheets in substantially the direction of travel of the sheets while the sheets are still traveling at high speed.

12. A sheet-feeding machine having, in combination, means for feeding sheets at relatively high speed past a predetermined point, means for thereafter feeding the sheets at relatively low speed to cause the sheets to become overlapped, means for stiffening the head of each sheet as it passes the point, and means for thereafter directing air currents under the heads of the sheets.

13. A sheet-feeding machine having, in combination, means for feeding sheets at relatively high speed, means for thereafter feeding the sheets at relatively low speed to cause the sheets to become overlapped, means for blowing under the heads of the sheets to stiffen them, and means for thereafter directing air currents under the heads of the sheets.

14. A sheet-feeding machine having, in combination, high-speed means for feeding sheets at relatively high speed, low-speed means for thereafter feeding the sheets at relatively low speed to cause the sheets to become overlapped in a moving pile, and means for directing air currents under the heads of the sheets between the high-speed means and the low-speed means while the sheets are still traveling at high speed in the general direction of travel of the sheets.

15. A sheet-feeding machine, having, in combination, a relatively high-speed tape for feeding sheets at relatively high speed, a relatively low-speed tape lapped by the high-speed tape for thereafter feeding the sheets at relatively low speed to cause the sheets to become overlapped, and means for directing air currents under the heads of the sheets between the tapes while the sheets are still traveling at high speed and before their speed is changed.

16. A sheet-feeding machine having, in combination, a relatively high-speed tape for feeding sheets at relatively high speed, a relatively low-speed tape lapped by the high-speed tape for thereafter feeding the sheets at relatively low speed to cause the sheets to become overlapped, means for stiffening the heads of the sheets, and means for thereafter directing air currents under the heads of the sheets between the tapes while they are still traveling at high speed and before their change in speed.

17. A sheet-feeding machine having, in combination, means for feeding sheets at relatively

high speed, means for thereafter feeding the sheets at relatively low speed to cause the sheets to become overlapped in a moving pile, and means for directing air currents under the heads of the sheets in substantially the direction of travel of the sheets at a speed higher than the speed of travel of the sheets while the sheets are still traveling at high speed and before their change in speed.

18. A sheet-feeding machine having, in combination, means for feeding sheets at relatively high speed, means for thereafter feeding the sheets at relatively low speed to cause the sheets to become overlapped in a moving pile, and means for directing air currents into the space between a high-speed sheet and a previously fed low-speed sheet in substantially the direction of travel of the sheets.

19. A sheet-feeding machine having, in combination, means for feeding sheets, a table, and means for directing air currents against the table and beyond the table under a sheet in the direction of travel of the sheet.

20. A sheet-feeding machine having, in combination, a relatively high-speed tape for feeding sheets at relatively high speed, a relatively low-speed tape for thereafter feeding the sheets at relatively low speed to cause the sheets to become overlapped, a table positioned between the high-speed tape and the low-speed tape and extending in the direction of travel of the sheets, and means for directing air currents under the table and beyond the table into the space between a high-speed sheet and a previously fed low-speed sheet.

21. A method of feeding sheets that comprises feeding sheets over a support, depositing the sheets upon the support, blowing under the heads of the sheets while they are still traveling over the support, and shielding a portion of the body of each sheet from the blowing action during the blowing action under the heads of the sheets.

22. A method of feeding sheets that comprises feeding sheets over a support, depositing the sheets upon the support, stiffening the head of each sheet, blowing under the heads of the sheets while they are still traveling over the support, and shielding a portion of the body of each sheet from the blowing action during the blowing action under the heads of the sheets.

23. A method of feeding sheets that comprises feeding sheets at relatively high speed, thereafter feeding the sheets at relatively low speed to cause the sheets to become overlapped, directing air currents under the head of a high-speed sheet into the space between said high-speed sheet and a previously fed low-speed sheet in the direction of extension between the sheets, and shielding a portion of the body of each sheet from the blowing action during the blowing action under the heads of the sheets.

24. A method of feeding sheets that comprises feeding a sheet successively past two predetermined points, blowing under the head of the sheet in a fixed direction substantially at right angles to the direction of travel of the sheet as the sheet passes one of the points, and thereafter blowing under the head of the sheet in substantially the direction of travel of the sheet at the other point.

25. A sheet-feeding machine having, in combination, means for feeding sheets at relatively high speed, means for thereafter feeding the sheets at relatively low speed to cause the sheets to become overlapped, a table, and means for

directing air currents against the table and beyond the table under the heads of the sheets in substantially the direction of travel of the sheets while the sheets are still traveling at high speed.

5 26. A sheet-feeding machine having, in combination, means for feeding sheets, a table disposed crosswise of the direction of feed, the feeding means being adapted to feed the sheets over the table and beyond the table in the direction of feed, and means for directing air currents against the table and under a portion of a sheet that has traveled beyond the table in the direction of feed.

10 27. A sheet-feeding machine having, in combination, means for feeding sheets at relatively high speed, means for thereafter feeding the sheets at relatively low speed to cause the sheets to become overlapped, a table positioned crosswise of the direction of feed between the high-speed feed means and the low-speed feed means 15 and extending in the direction of travel of the sheets, and means for directing air currents under the table and beyond the table into the space between a high-speed sheet and a previously fed low-speed sheet.

20 28. A method of feeding sheets that comprises feeding sheets at relatively high speed in a predetermined direction, thereafter feeding the sheets at relatively low speed in the said direction to cause the sheets to become overlapped 25 in a moving pile, and blowing under the heads of the sheets while they are still traveling at high speed and until their speed is changed.

29. A method of feeding sheets that comprises 30 feeding sheets at relatively high speed, thereafter feeding the sheets at relatively low speed while continuing to feed other sheets at relatively high speed to cause the sheets to become overlapped in a moving pile, and blowing under the heads of the sheets while they are still traveling at high speed and until their speed is changed.

35 30. A method of feeding sheets that comprises feeding sheets at relatively high speed in a predetermined direction, thereafter feeding the sheets at relatively low speed in the said direction to cause the sheets to become overlapped in a moving pile, stiffening the head of each sheet, and thereafter blowing under the heads of the sheets while they are still traveling at high speed 40 and until their speed is changed.

45 31. A method of feeding sheets that comprises feeding sheets at relatively high speed at a predetermined speed in a predetermined direction past a predetermined point, stiffening the heads of the sheets as they pass the point, thereafter feeding the sheets at relatively low speed in the said direction to cause the sheets to become overlapped in a moving pile, and blowing under the heads of the sheets while they are still traveling at high speed and until their speed is changed.

50 32. A sheet-feeding machine having, in combination, means for feeding sheets at relatively high speed in a predetermined direction, means for thereafter feeding the sheets at relatively low speed in the said direction to cause the sheets to become overlapped in a moving pile, and means for directing air currents under the heads of the sheets in substantially the direction of travel of the sheets while the sheets are still traveling at high speed.

55 33. A sheet-feeding machine having, in combination, means for feeding sheets at relatively high speed, means for thereafter feeding the sheets at relatively low speed while the first-

named means continue to feed the sheets at relatively high speed to cause the sheets to become overlapped in a moving pile, and means for directing air currents under the heads of the sheets in substantially the direction of travel of the sheets while the sheets are still traveling at high speed.

34. A sheet-feeding machine having, in combination, means for feeding sheets at relatively high speed, means for thereafter feeding the sheets at relatively low speed to cause the sheets to become overlapped, means for stiffening the head of each sheet, and means for directing air currents under the heads of the sheets in substantially the direction of travel of the sheets while the sheets are still traveling at high speed.

35. A sheet-feeding machine having, in combination, means for feeding sheets, a table disposed crosswise of the direction of feed, a support beyond the table, the feeding means being adapted to feed the sheets over the table and beyond the table over the support in the direction of feed, and means for directing air currents against the table and between the support and a portion of a sheet that has traveled beyond the table in the direction of feed.

36. A sheet-feeding machine having, in combination, means for feeding sheets, a table disposed crosswise of the direction of feed, means disposed beyond the table in the direction of the feed for feeding the sheets further, the first-named feeding means being adapted to feed the sheets over the table and beyond the table to the second-named feeding means, and means for directing air currents against the table and between the second-named feeding means and a portion of a sheet that has traveled beyond the table over the second-named feeding means.

37. A sheet-feeding machine having, in combination, means for feeding sheets at relatively high speed, means for thereafter feeding the sheets at relatively low speed to cause the sheets to become overlapped, a table disposed crosswise of the direction of feed between the high-speed feed means and the low-speed feed means and extending in the direction of travel of the sheets, a support beyond the table, the feeding means being adapted to feed the sheets over the table and beyond the table over the support in the direction of feed, and means for directing air currents under the table and beyond the table into the space between a high-speed sheet and a previously fed low-speed sheet on the support.

38. A sheet-feeding machine having, in combination, means for feeding sheets, a table disposed crosswise of the direction of feed, a support beyond the table, the feeding means being adapted to feed the sheets over the table and beyond the table over the support in the direction of feed,

means for directing air currents against the table and between the support and a portion of a sheet that has traveled beyond the table in the direction of feed, and means for thereafter feeding the sheets further.

39. A sheet-feeding machine having, in combination, means for feeding sheets, a table disposed crosswise of the direction of feed, the feeding means being adapted to feed the sheets over the table and beyond the table in the direction of feed, and means for directing air currents in the direction of travel of the sheet over the table and against the table and under a portion of a sheet that has traveled beyond the table in the direction of feed.

40. A method of feeding sheets that comprises feeding a sheet successively past two predetermined points and directing two air blasts in different directions with respect to the sheet under the sheet at the respective points.

41. A sheet-feeding machine having, in combination, means for feeding a sheet successively past two predetermined points, means for blowing under the head of the sheet in a fixed direction as the sheet passes one of the points, and means for blowing under the head of the sheet in a second fixed direction different from the first direction with respect to the sheet as the sheet passes the other point.

42. A method of feeding sheet material that comprises feeding a sheet at different speeds, and blowing under the head of the sheet just before the speed is changed.

43. A sheet-feeding machine having, in combination, means for feeding sheets at relatively high speed, means for thereafter feeding the sheets at relatively low speed to cause the sheets to become overlapped in a moving pile, and means operable just prior to changing the speed of the sheets for supplying air currents to the heads of the sheets.

44. A method of feeding sheets that comprises feeding sheets first at relatively high speed and then at relatively low speed to cause the sheets to become overlapped in a moving pile, and blowing under the head of each sheet just prior to changing its speed.

45. A method of feeding sheets that comprises feeding a plurality of sheets continuously in a predetermined direction at a predetermined speed successively past a predetermined point, feeding the sheets continuously in the said direction at a lower speed after passing the point to cause the sheets to become lapped in a moving pile during their continuous feeding in the said direction, and blowing under the head of each sheet just before the speed is changed and after the said head of the sheet has passed the point.

LOUIS L. MATTHEWS.
